UNITED STATES PATENT OFFICE.

LEVETT A. LONG, OF DAYTON, OHIO.

INSOLE.

1,092,373.

Specification of Letters Patent. Patented Apr. 7, 1914.

Application filed December 1, 1913. Serial No. 803,880.

To all whom it may concern:

Be it known that I, LEVETT A. LONG, a citizen of the United States, residing at Dayton, in the county of Montgomery and State of Ohio, have invented certain new and useful Improvements in Insoles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in insoles for shoes.

The object of the invention is to provide a device of this type which is instrumental in producing a sensation of warmth to the feet of the wearer.

Referring to the accompanying drawings, Figure 1 is a top plan view of my improved insole with parts broken away; and Fig. 2 is a section on the line $a-a$ of Fig. 1.

In the specification and drawings, similar reference characters indicate corresponding parts.

Referring more particularly to the drawings, 1 represents a layer of pervious material which may be made of any suitable wool or cotton fabric. The insole, of which 1 is the upper layer, is also provided with a lower or bottom layer 3 of impervious material such as leather or rubber. The insole is formed of laminations, and the pile thus constructed is cut into suitable shapes so

that they may be easily worn in the shoe. The upper layer 1 comes in contact with the sole of the foot. To create a sensation of warmth a suitable chemical irritating medium such as a layer 4 is provided. This last named layer is formed of Cayenne pepper or capsicum and is interposed between the upper and lower layers 1 and 3. The capsicum is preferably mixed with wool and united by any suitable form of binder such as an antiseptic adhesive. When the insole is in use, the moisture from the feet is sufficient to dissolve a portion of the active principle of the chemical irritant which comes in contact with the sole of the foot when the fabric 1 becomes moistened. The effect of the capsicum will be to draw the blood of the body to the feet thereby producing a sensation of warmth.

Having described my invention, I claim.

1. An insole comprising an upper layer of pervious material, a lower layer of impervious material, and a layer interposed between said upper and lower layers and a constituent of which is capsicum.

2. An insole, comprising an upper layer of pervious material, a lower layer of impervious material, and an intermediate layer of chemical irritant material consisting of capsicum, wool and a suitable binder.

In testimony whereof I affix my signature, in presence of two witnesses.

LEVETT A. LONG.
